HARRY A. DAVIS, OF HOPEDALE, MASSACHUSETTS, ASSIGNOR TO DRAPER COMPANY,
OF HOPEDALE, MASSACHUSETTS, A CORPORATION OF MAINE.

SHUTTLE-FEELER MECHANISM FOR LOOMS.

1,091,813.

Specification of Letters Patent. Patented Mar. 31, 1914.

Application filed March 10, 1913. Serial No. 753,283.

To all whom it may concern:

Be it known that I, HARRY A. DAVIS, a citizen of the United States, residing at Hopedale, county of Worcester, State of Massachusetts, have invented an Improvement in Shuttle-Feeler Mechanism for Looms, of which the following description, in connection with the accompanying drawing, is a specification, like characters on the drawing representing like parts.

This invention relates to looms of the type wherein the running filling is replenished prior to complete exhaustion and in which a shuttle feeler is employed to restrain the operation of the replenishing mechanism in case of an improperly boxed shuttle, and in which means are provided for parting the spent filling between the cloth and the shuttle, such parting means being usually supported by, or to move with, the shuttle feeler.

The construction and operation of shuttle feelers and thread clamping and parting instrumentalities have been the subject of a number of patents and these matters are familiar to any one skilled in this art. The shuttle feeler is commonly mounted on a swinging or pivoted support to move toward and from the lay and to pass in front of the shuttle nose when the lay beats up and the shuttle is properly boxed at the replenishing end of the loom. Upon the call for replenishment the shuttle feeler is actuated but if the shuttle is improperly boxed the shuttle feeler, contacting therewith, restrains the operation of the filling replenishing mechanism. The thread clamping and parting means, usually carried by and moving with the shuttle feeler, seize the filling of the filling carrier to be abandoned, sever it near the shuttle, clamp the end and carry it forward so as to bring the filling into the field of the usual temple thread cutter which thereupon severs the end of the filling close to the edge of the cloth. The thread clamping and parting instrumentalities as it moves forward from the fell must also move toward the edge of the cloth else it would stretch and break the filling end as it extends from the clamp to the fell. It not infrequently happens that the conditions are such that while the operation of the replenishing mechanism is restrained through the action of the shuttle feeler, yet nevertheless such a movement of the thread

clamping and parting instrumentality takes place, especially when the instrumentality is carried by the shuttle feeler, as to result in the actuation of the thread parting means. When this happens severance occurs without filling replenishment and consequently two empty picks will be made in the cloth with the consequent objectionable thin place.

The objects of this invention are to provide a shuttle feeler mechanism in which the shuttle feeler support shall be reciprocated rectilinearly, thus doing away with a pivotally mounted or swinging support and enabling the shuttle feeler to slide back and forth and a simple and efficient construction to be provided for its operation. Furthermore the invention enables the shuttle feeler and its support to be mounted above the plane of the cloth where it is readily accessible. This enables the shuttle feeler mechanism to be constituted as a substantially self-contained structure, which may be made up and fastened to the hopper or magazine stand or other suitable portion of the frame at the top of the loom frame. When, as herein shown, the thread clamping and parting means are carried by the shuttle feeler, the entire mechanism, including the thread clamping and parting means, is thus also mounted at the top of the loom and becomes a substantially self-contained structure which may be built and secured to the hopper or magazine stand or the loom frame at the top of the loom.

Another object of the invention resides in the construction and operation of the thread clamping and parting means. In Patent No. 1,084,878, granted January 20th, 1914, on an application filed concurrently herewith, I have disclosed such a means operated only upon the actual transference of the filling carrier to the lay so that there can be no parting of an unabandoned filling by the thread parting means and in which the actuation of the thread parting means is effected by or through the transfer of the fresh filling carrier. The object of the present invention in this feature is to provide a simple and efficient means for supporting and operating the thread clamping and parting means only upon the actual transference of the filling carrier, and preferably through the agency of the usual yielding bobbin support.

These and other objects of the invention

will appear more fully from the accompanying description and drawings and will be particularly pointed out in the appended claims.

- The invention may be embodied in various specific forms of construction, depending upon the character of filling replenishing loom to which it may be applied. To illustrate the invention I have shown a preferred embodiment thereof in connection with a loom such as the well-known Northrop loom, in which the filling carriers are bobbins, the fresh bobbins being supported in a rotary hopper or magazine and transferred therefrom upon call by a transferring device to the shuttle on the lay. The drawings illustrate such a preferred form of the invention as embodied in the Northrop type of weft replenishing loom.
- In the drawings—Figure 1 is a transverse section of a portion of the automatic filling replenishing loom having one embodiment of my present invention applied thereto, the lay being shown in full lines on back center and in dotted lines on front center, and only those parts being shown which are necessary to an understanding of the invention. Fig. 2 is a side elevation partially in vertical cross section of a portion of the mechanism shown in Fig. 1 with the shuttle feeler in its rearward position nearest the lay and with the thread clamping and parting means opened. Fig. 3 is a front elevation partially in vertical cross section of that portion of the loom shown in Fig. 1. Fig. 4 is a detail in front elevation of a portion of the lay showing the trip or bunter mechanism. Fig. 5 is a detail view in horizontal section on the line X—X of Fig. 3. Fig. 6 is a detail view in side elevation of a modification of the connections for operating the shuttle feeler.
- The lay A³; transferer f' to remove the filling carriers, or in this case the bobbins b^x, from the filling magazine or hopper F to the shuttle S when in the box at the replenishing side of the loom; the controlling rock shaft d' and its adjuncts; the shuttle feeler 9; the fixed and movable blades 16' 17' carried by the feeler and the plate 19 constituting the fixed member of the thread clamp; the usual guide stop h' against which the filling carrier or bobbin b^x is brought in position for transfer; the yielding supported bobbin support consisting of a flat finger 20 on a swinging plate 21 provided with a hub 22, the said finger being located adjacent the inner face of the disk of the hopper and opposite the stop h'; the finger 23 upheld from the plate 21 and straddling the stand F² of the hopper; the pin 24 passing through the finger 23, the stand F² and into the finger or support 20, thus pivotally mounting the bobbin support 20 and its connected parts on the stand F²; the

spring 25 held between the notched lug on the back of the stand and the head 27 of a slide rod 28 connected with the finger 23, the rod being guided in the notched lug so that the stop h' forms one side of a throat through which the filling carrier or bobbin passes to the shuttle, the yielding bobbin support or finger 20 forming the other side; are all parts, the construction and operation of which, except so far as hereinafter described, will be familiar to one skilled in the art, and are substantially the same as illustrated and described in my aforesaid patent.

The construction and operation of the specific devices which I have herein illustrated as a preferred form for embodying the present invention in a loom of the type illustrated, will now be described.

The shuttle feeler and the thread clamping and parting instrumentalities in the preferred form of this invention constitute, as has been pointed out, a substantially self-contained structure, which may be mounted or secured above the plane of the cloth and to some portion of the loom frame. As herein shown, these parts are mounted on a supporting bracket 40 having a socket 41 fitting over the transferer hub 42 and locked in place thereon by the set screw 43. 95 This supporting bracket 40 has an upwardly projecting arm 44 and a horizontal and forwardly projecting arm 45. The arm 45 terminates in a bearing socket 46 in which is secured by set screws 47 a guide bar 48 projecting rearwardly toward the lay.

The shuttle feeler support is constituted as a sleeve 49 mounted to slide or reciprocate rectilinearly upon the guide bar 48. A supporting arm 50 depends from the sleeve 49 and terminates in the shuttle feeler 9 of the usual construction already referred to. Upon this supporting arm 50 are mounted in the usual manner the fixed member 19 of the thread clamp and the fixed and movable blades 16' 17' of the thread parter and its adjuncts.

The upwardly extending bracket arm 44 terminates in a hub 51 having pinned therein and projecting therefrom a stub shaft 52. 115 A bell crank lever 53 is fulcrumed on the stub shaft 52 and is held in place by a cotter pin 54. A helical spring 55 surrounds the fulcrum sleeve of the bell crank lever 53 and is secured at one end 56 to the bell crank 120 lever and at the opposite end 57 to the hub 51. The spring is surrounded by a sleeve 58 pinned at 59 to the hub 51. The action of the spring 55 is such as to swing the depending arm 60 of the bell crank lever 53 125 toward the rear or toward the lay. The arm 60 is connected to the shuttle feeler support to cause the reciprocation of the latter. Since the shuttle feeler support also supports and carries the thread clamping and 130

parting instrumentalities, it is necessary for this reason, as already explained, that this support shall swing laterally or have a rotary movement on the guide bar 48 in order 5 to cause the thread clamping and parting instrumentalities to move toward the cloth as they come forward carrying the end of the abandoned filling. Accordingly in this 10 form of the invention the connection between the depending arm 60 of the bell crank lever and the shuttle feeler support 49 is such as to cause this movement to take place. The shuttle feeler support 49 is, therefore, provided with a laterally projecting arm 61 formed into a stud 62 at its 15 end fitting loosely in an aperture in the lower end of the arm 60. A spring 63 connected to the arm 60 and to a stud 64 projecting from the arm 60 holds the stud 62 20 snugly against the aperture in the arm 60 and prevents rattling and lost motion. It will thus be seen that as the bell crank lever swings about its fulcrum it causes a rectilinear reciprocating of the shuttle feeler 25 support, and by reason of the connection illustrated, also causes a swinging or rotary movement of the shuttle feeler support on its axis.

The controlling rock shaft d' has secured 30 thereto and projecting rearwardly therefrom the usual arm d^{12} . This arm is held yielding downward by the usual spring S^x and is raised by the rocking of the shaft d' whenever a replenishment of filling is called 35 for by means well known and common. The bell crank lever 53 in the form of the invention herein shown has its shorter arm 65 connected to the free end of the arm d^{12} by a link 66. This link is pivoted at its lower 40 end to the arm d^{12} and at its upper end is provided with a slot 67 fitting over a stud 68 on the arm 65. The parts therefore normally 45 occupy the position shown in Fig. 1, the spring S^x holding the arm d^{12} down and through the link 66 and the bell crank lever 53 holding the shuttle feeler support in its 50 forward position. When a replenishment of filling is called for the shaft d' rocks, raising the arm d^{12} , and consequently the link 66; and thereupon the spring 55 comes into 55 action swinging the bell crank lever 53 and moving the shuttle feeler support rearwardly.

The shuttle feeler may effect its functions 60 in various ways, but as an efficient and simple construction I have provided the mechanism now to be described.

The transferrer f' pivotally mounted on the transferrer hub carries a downwardly 65 projecting forked arm 70. A stud 71 is pivoted in the lower end of the forked arm 70 and a coil spring 72 is attached at one end to the forked arm 70 and at the other end to the head of the stud 71. A transferrer operating dog is shown comprising a nose

piece 73 and a support 74. The support 74 is rigidly connected to the stud 71 and the nose piece 73 is adjustably mounted on the support, being provided with a groove 75 sliding on a rib 76, a bolt 77 holding the parts together. A set screw 78 passing through the support, engaging the nose piece 73 and provided with a lock nut 79, enables an accurate adjustment to be made. It will be seen that the spring 72 acts to hold the free end of the nose piece upward and to guide it against the extended portion 80 of the base plate of the hopper F^2 so that the effective end of the nose piece moves rectilinearly. The bunter in this form of the mechanism is moved by the shuttle feeler into position to strike the dog and cause the operation of the transferrer. The bunter C^2 is carried by a horizontal shaft 81 journaled in bearings 82 projecting from a base plate 89 secured on the face of the lay A^3 , and a trip 83 is likewise secured to the shaft 81 in the path of a heel 84 depending from the shuttle feeler support. A coil spring 85 connected at one end to the shaft 81 and the other end to one of its bearings 82 acts normally to swing the bunter and trip forwardly into the position, as shown in Fig. 1. A set screw 86 serves to adjust the trip 83 rotarily on the shaft 81 and a set screw 87 passing through a depending lug 88 from the bunter abuts against the base plate 89, thus serving to adjust the forward position of the bunter and trip.

In the operation of the mechanism, when a replenishment of filling is called for, the shuttle feeler support 49 is moved rearward rectilinearly on the guide bar 48 until it is stopped by the pin 90 at the rearward end of the guide bar, entering a slot 91 in the end of the shuttle feeler support. This construction not only limits the rearward movement of the shuttle feeler support, but locks it against twisting on the guide bar. If the shuttle is properly boxed when the lay beats up the trip 83 striking the heel 84 of the shuttle feeler support will throw the bunter C^2 into position, so that it will strike the nose piece 73 and operate the transferrer f' to effect the filling replenishment. If, however, the shuttle is improperly boxed, the shuttle feeler will contact with the shuttle, the trip 83 will not reach the heel 84, the bunter C^2 will accordingly not be swung into position to strike the nose piece 73, and the shuttle feeler and its support will be pushed forwardly by the shuttle on the guide bar 48 and there will be no actuation of the trans- 115 ferrer.

The invention also provides, as has been 120 explained, means for securing the operation of the thread clamping and parting instrumentalities only upon the actual transference of the filling carrier from the magazine or hopper to the lay. In the construction 125

illustrated the movable member 17' of the thread clamp and parter is provided with an upwardly extending ear 92, which, when the shuttle feeler support 49 is moved rearwardly on the guide bar 48, comes in contact with the lower end of the pin 90, the shuttle feeler support being cut away at the bottom, as shown at 93, for that purpose. Thus, when the shuttle feeler support reaches its rearward position, the thread clamping and parting means are opened. The closing action of the thread clamping and parting means is effected by a striker arm 31 movable with the bobbin support 20. In the constriction illustrated this striker arm 31, shown as an L-shaped bar, is locked in place by set screws 32 in a bored out projection 30 in the finger 23, already described, and is thus both longitudinally and rotarily adjustable to give any desired position to the free end of the striker arm. When the shuttle feeler support is in its rearward position, as shown in Fig. 2, the surface 94 of the movable member 17' of the thread clamping and parting instrumentality is beneath the free end of the striker arm 31, so that if, and only if, the bobbin support 20 is moved downwardly to allow of the discharge of the bobbin, the striker arm will be moved simultaneously contacting with the surface 94 and operating the movable member 17' to clamp and part the filling.

Fig. 6 of the drawing shows a modification of the means for securing the actuation of the shuttle feeler support from the arm d^{12} . In the construction already described, it will be noted that the spring S^x acts to swing the bell crank lever 53 to move the shuttle feeler support forwardly, while the spring 55 acts to swing the bell crank lever 53 in the opposite direction, these two springs being thus opposed to each other in their action, and the spring S^x being by far the more powerful. In the construction shown in Fig. 6 I obviate this opposition of two springs and secure the desired results by the use of but a single spring. In this Fig. 6 d' is the controlling rock shaft, d^{12} the arm connected thereto, 49 the shuttle feeler support, 48 the guide bar therefor, 53 the bell crank lever, all as just described. In the construction of Fig. 6 there is, however, no spring at the hub of the lever 53. The link 660 is pivoted at its upper end directly to the short arm of the bell crank lever 53, and at its lower end to a lever 661 fulcrumed at 662 to the end of the arm d^{12} . The opposite end of the lever 661 is connected to the usual spring S^x and this end of the lever contacts at 663 with the arm d^{12} . The operation of this construction will be apparent. The arm d^{12} rises upon the call for replenishment and the spring S^x holding the lever 661 in contact with the arm d^{12} lifts the link 660 and thereby the

bell crank lever 53 swings to move the shuttle feeler support rearwardly. The spring S^x returns the parts to the position shown in Fig. 6, and when the shuttle feeler support is moved forwardly with the arm d^{12} still raised, the lever 661 rocks on its fulcrum against the action of the spring S^x . Thus the same results are secured by the use of a single spring as in the construction previously described.

Having fully described my invention, what I claim as new and desire to secure by Letters Patent is:—

1. An automatic filling replenishing loom comprising a bracket presenting horizontal and vertical arms, a rectilinear guide bar mounted in and projecting from the horizontal arm, a shuttle feeler, a support for the shuttle feeler mounted to reciprocate on said guide bar to carry the feeler into and out of feeling position, and means actuated upon the call for filling replenishments mounted upon said vertical arm and connected to said support for moving the same.

2. An automatic filling replenishing loom comprising a bracket presenting horizontal and vertical arms, a rectilinear guide bar mounted in and projecting from the horizontal arm, a shuttle feeler, a support for the shuttle feeler mounted to reciprocate on said guide bar to carry the feeler into and out of feeling position, a bell crank lever fulcrumed on said vertical arm having one arm connected to the said support, and means connected to the other arm of said bell crank lever and controlling the movement thereof upon the call for filling replenishment.

3. An automatic filling replenishing loom comprising a bracket presenting horizontal and vertical arms, a rectilinear guide bar mounted in and projecting from the horizontal arm, a shuttle feeler, a support for the shuttle feeler mounted to reciprocate on said guide bar to carry the feeler into and out of feeling position, a bell crank lever fulcrumed on said vertical arm, one arm of said bell crank lever being connected to said support, a spring connected to and moving the bell crank lever to move the support and carry the shuttle feeler into feeling position, and means connected to the other arm of said bell crank lever to control the movement thereof upon the call for filling replenishment.

4. An automatic filling replenishing loom comprising a bracket presenting horizontal and vertical arms, a rectilinear guide bar mounted in and projecting from the horizontal arm, a support mounted to slide and rotate on said guide bar, a thread clamping and parting means mounted on said support, an arm projecting laterally from said support, a lever fulcrumed on the vertical bracket arm and connected to said laterally.

- projecting arm, and means for swinging said lever controlled by the call for filling replenishment, whereby upon the movement of said lever a simultaneous rectilinear and rotary movement is given to the said support, thus preventing the thread clamping means from breaking the filling as it comes forward carrying the filling end. 5
5. An automatic filling replenishing loom comprising a rectilinear guide bar supported above the plane of the cloth, a sleeve support mounted to slide and rotate on said guide bar, a shuttle feeler and thread clamping and parting means mounted on and carried by said support, and means controlled by the call for filling replenishment to cause the simultaneous rectilinear and rotary movement of said sleeve on said guide bar. 10
6. An automatic filling replenishing loom comprising a shuttle feeler, a support therefor, and means for guiding said support rectilinearly during the movement of the feeler into and out of feeling position. 15
7. An automatic filling replenishing loom comprising a shuttle feeler, a support therefor, a rectilinear guide for said support, whereby the shuttle feeler support moves rectilinearly to carry the feeler into and out of feeling position. 20
8. An automatic filling replenishing loom comprising a bracket, a rectilinear guide on said bracket, means for securing the bracket to the loom frame to locate said guide above the plane of the cloth, a shuttle feeler, a shuttle feeler support mounted to slide on said guide, and means carried by said bracket for sliding said support to bring the feeler into feeling position. 25
9. An automatic filling replenishing loom comprising a rectilinear guide, a support mounted for rectilinear and rotary movement on said guide, a shuttle feeler and thread clamping and parting means mounted on said support, and means for giving a partial rotation to said support as it moves forward on said guide with the thread clamping means carrying the filling end. 30
10. An automatic filling replenishing loom comprising a support, a shuttle feeler and thread clamping and parting means mounted on said support, and means for giving a simultaneous rectilinear and rotary movement to said support to move the feeler into and out of feeling position and to prevent breaking of the filling as the thread clamping means moves forward carrying the filling end. 35
11. In an automatic filling replenishing loom comprising a lay, a replenishing magazine for the fresh filling carriers and a transerrer for transferring a fresh filling carrier from the magazine to the lay, the combination of a rectilinearly movable support, a shuttle feeler and thread clamping and parting means mounted on said support, and means actuated by or through the transfer of the fresh filling carrier from the magazine to the lay to actuate the thread clamping and parting means to clamp and part the thread of the filling carrier to be abandoned. 70
12. An automatic filling replenishing loom comprising a hopper for the fresh filling carriers, a filling carrier support movable to release a fresh filling carrier from the hopper, a rectilinear guide, thread clamping and parting means supported and movable on said guide, and means carried by and movable with said filling carrier support to actuate the thread clamping and parting means to clamp and part the thread of the filling carrier to be abandoned. 75
13. An automatic filling replenishing loom comprising a hopper for the fresh filling carriers, a filling carrier support movable to release a fresh filling carrier from the hopper, a rectilinear guide, thread clamping and parting means supported and movable on said guide, and means carried by and movable with said filling carrier support to actuate the thread clamping and parting means to clamp and part the thread of the filling carrier to be abandoned, and means carried by said guide for opening the thread clamping and parting means when moved to rearward position. 80
14. An automatic filling replenishing loom comprising a hopper for the fresh filling carriers, a filling carrier support movable to release a fresh filling carrier from the hopper, a rectilinear guide bar, thread clamping and parting means supported from and guided on said guide bar, an arm carried by and movable with said filling carrier support and having its end projecting over the thread clamping and parting means to clamp and part the thread of the filling carrier to be abandoned upon the releasing movement of said filling carrier support. 85
15. An automatic filling replenishing loom comprising a rectilinear guide bar, a support mounted to move rectilinearly on said guide bar, a shuttle feeler carried by said support, a heel projecting from said support forward of the shuttle feeler, a lay, a replenishing magazine for the fresh filling carriers, a transerrer for transferring a fresh filling carrier from the magazine to the lay, a latch connected to the transerrer, a bunter and connected trip pivotally mounted on the face of the lay, the said trip coöperating with the said heel to throw the bunter into contact with the latch when the lay beats up and the shuttle feeler is in its rearmost position. 90
16. An automatic filling replenishing loom comprising a hopper for the fresh bobbins, a bobbin support movable to release a fresh bobbin from the hopper, a rectilinear guide 128

6
bar, a thread clamping and parting means mounted from and movable on said guide bar, the said thread clamping and parting means including a movable member, an ear 5 projecting from said movable member, a stop on said guide in the path of said ear and adapted to be struck thereby and move said member to open the clamp and part upon the rearward movement thereof, and a 10 striker arm connected to and movable with

the bobbin support to strike and actuate said movable member to clamp and part the filling upon the transfer of a bobbin.

In testimony whereof, I have signed my name to this specification, in the presence of 15 two subscribing witnesses.
